UNITED STATES PATENT OFFICE.

JAMES E. MARSDEN, OF FOND DU LAC, WISCONSIN.

PRINTING ATTACHMENT FOR PAPER-HOLDERS.

SPECIFICATION forming part of Letters Patent No. 579,155, dated March 23, 1897.

Application filed October 23, 1895. Serial No. 566,645. (No model.)

To all whom it may concern:

Be it known that I, JAMES E. MARSDEN, a citizen of the United States, residing at Fond du Lac, in the county of Fond du Lac and State of Wisconsin, have invented a new and useful Printing Attachment for Paper Holders and Cutters, of which the following is a specification.

The invention relates to improvements in printing attachments for paper holders and cutters.

The object of the present invention is to provide for roll-paper holders and cutters a printing attachment which will be simple and inexpensive in construction and readily applicable to all kinds of roll-paper holders and cutters, and which will be capable of printing an advertisement or other matter on the paper as it is reeled off the roll.

The invention consists in the construction and novel combination and arrangement of parts hereinafter fully described, illustrated in the accompanying drawings, and pointed out in the claims hereto appended.

In the drawings, Figure 1 is a side elevation of a paper holder and cutter provided with a printing attachment constructed in accordance with this invention. Fig. 2 is an end elevation of the same. Fig. 3 is a detail perspective view of the printing attachment. Fig. 4 is a sectional view of the inking device, taken longitudinally of the printing-roll. Fig. 5 is a similar view taken transversely of the printing-roll.

Like numerals of reference designate corresponding parts in all the figures of the drawings.

1 designates a supporting-frame comprising a base, vertical standards 2, and a top piece 3, connecting the standards, and the latter are provided with suitable bearings and have journaled on them a roll 4 of paper. At the front side of the device is arranged a cutter 5 and at the rear side thereof is located a printing attachment 6.

The printing attachment comprises a printing-roll 7, journaled in a hanger 8, and an inking mechanism. The hanger comprises a bar 9, provided with depending arms to receive the printing-roll 7 and its upwardly-extending arms 10, which are hinged to attachment plates or bars 11. The attachment

plates or bars are secured to the lower edge of the top piece 3, and the printing attachment is disposed at an inclination, and the 55 printing-roll is held in contact with the roll of paper by springs 12, having their terminals connected to the arms 10 and to the attachment bars or plates.

The printing-roller is provided at its ends 60 with elastic bands 13, which bear against the roll of paper at the ends thereof and prevent the paper from slipping and passing the roller without rotating the same. The end bands 13 are located directly over the wooden plugs 65 or cores, which are usually inserted in the ends of the roll, and a firm bearing is obtained. The top is arranged at the center of the printing-roll and is supplied with ink by means of a pair of inking-rolls 14, arranged 70 parallel with each other and journaled in a vertical movable bearing-frame 15, which is arranged in a rectangular portion or bend 16 of the hanger. The bearing-frame is composed of a top piece and depending ends 75 which are provided with lugs 17, located at opposite sides of the hanger and form ways. The printing-rolls are yielding held against the type by a spring 18, arranged at the top of the bearing-frame within the loop and centrally secured to the top thereof and having its ends free and bearing against the frame 80 15. The ends of the inking-rolls rest upon elastic bands 20, which also bear against the roll of paper and which prevent the type from 85 being injured and insure a good impression.

Ink is supplied to the inking-rolls by means of a brush 21, mounted on the rectangular bend of the hanger and provided at opposite sides thereof with longitudinal series of tufts 90 22, of bristles, which bear against the inking-rolls. The back of the brush is provided with a series of passages 23, which lead to the tufts 22 and which are adapted to convey ink to the latter, and the brush operates to spread the 95 ink evenly on the ink-rolls. As the paper is reeled from the roll 4 the printing-roller is rotated, bringing the type in contact with the paper and printing thereon advertising or other matter.

It will be seen that the printing attachment for paper holders and cutters is exceedingly simple and inexpensive in construction, that it is positive and reliable in operation, and

that it will insure a perfect impression and will evenly distribute the ink and prevent blurring or smearing.

Changes in the form, proportion, and minor details of construction may be resorted to without departing from the principle or sacrificing any advantages of the invention, such as varying the length of the printing-roll and adapting the hanger to the frame of 10 the paper holder and cutter to which the attachment is to be applied.

What I claim is—

1. A printing attachment for paper holders and cutters comprising a hanger designed to 15 be hinged to the frame of a paper holder and cutter, a printing-roll journaled in the hanger, an inking-roll mounted in the hanger and yieldingly contacting with the printing-roll, and a brush engaging the inking-roll and provided with ink-passages, substantially as and 20 for the purpose described.

2. A printing attachment for paper holders and cutters comprising a hanger provided with a rectangular bend, a printing-roll journaled in the hanger and located adjacent to 25 the bend, a bearing-frame arranged within the hanger and slidably connected with the same at the sides of the bend, inking-rolls journaled in the bearing-frame and contact-

ing with the printing-roll, a spring engaging 30 the bearing-frame, and holding the inking-rolls against the printing-roll, and a brush mounted on the hanger at the top thereof, and provided at opposite sides of the same with tufts, and having ink-passages communicating with the tufts, substantially as described. 35

3. A printing attachment for paper holders and cutters, comprising a hinged hanger provided with a rectangular portion, a printing-roll journaled in the hanger and located adjacent to the rectangular portion, a bearing-frame arranged within the rectangular portion of the hanger and slidably connected with the sides of the same, a pair of inking-rolls journaled on and carried by the bearing-frame, and a single spring interposed between the bearing-frame and the top of the rectangular portion of the hanger and holding both inking-rolls in contact with the printing-roll, 40 substantially as described. 45

In testimony that I claim the foregoing as my own I have hereto affixed my signature in the presence of two witnesses.

JAMES E. MARSDEN.

Witnesses:

FRANK W. FOX,

PETER JACOB WIEKERT.
